UNITED STATES PATENT OFFICE

LESLIE A. BROWN, OF MERIDEN, CONNECTICUT, ASSIGNOR TO INTERNATIONAL SILVER COMPANY, OF MERIDEN, CONNECTICUT, A CORPORATION OF NEW JERSEY

DESIGN FOR A SPOON OR OTHER ARTICLE OF TABLEWARE

Application filed April 2, 1931. Serial No. 39,339. Term of patent 7 years.

To all whom it may concern:

Be it known that I, LESLIE A. BROWN, a citizen of the United States, residing at Meriden, county of New Haven and State of Connecticut, have invented a new, original, and ornamental Design for a Spoon or Other Article of Table-ware, of which the following is a specification, reference being had to the accompanying drawings, forming a part thereof.

Fig. 1 is a front elevation of a spoon showing my new design; and

Fig. 2 is a cross-sectional view on the line 2—2 of Fig. 1.

The back of the spoon conforms with the disclosure in Fig. 2, and the center panel may be plain or have surface ornamentation embodying the motif disclosed in Fig. 1.

I claim:

The ornamental design for a spoon or other article of table-ware, as shown and described.

LESLIE A. BROWN.
